UNITED STATES PATENT OFFICE.

JAMES W. ARROTT, JR., OF ALLEGHENY, PENNSYLVANIA.

ENAMELING-TABLE.

SPECIFICATION forming part of Letters Patent No. 558,339, dated April 14, 1896.

Application filed August 22, 1895. Serial No. 560,151. (No model.)

To all whom it may concern:

Be it known that I, JAMES W. ARROTT, Jr., a citizen of the United States, residing at Allegheny, in the county of Allegheny and State 5 of Pennsylvania, have invented certain new and useful Improvements in Enameling-Tables; and I do hereby declare the following to be a full, clear, and exact description of the invention, such as will enable others skilled 10 in the art to which it appertains to make and use the same.

My invention has relation to enameling-tables, and relates particularly to tables for heavy metallic objects, such as iron bath-tubs, 15 tanks, sinks, &c.; and my invention has for its object the provision of novel means by which the article to be enameled can be easily and speedily placed in any desired position, so as to enable the operatives to perform their 20 work with ease and despatch.

While I have stated that my invention relates to enameling-tables, I wish it to be understood that my invention comprehends an 25 adjustable revolving table for handling either regularly or irregularly shaped vessels or articles for the purpose of accurately and rapidly or slowly adjusting them to any desired position necessary for subjecting their various surfaces to any desired treatment when 30 either hot or cold.

In carrying my invention into effect I provide a revoluble and tiltwise-adjustable table mounted on suitable supports and provided with novel means for holding the article in 35 position while being treated, for revolving the table, for adjusting the same to any desired angle, and for protecting parts of the surface, when necessary or desirable, during the enameling or other operation.

My invention consists in the novel construction, combination, and arrangement of parts 40 hereinafter described.

Referring to the accompanying drawings, which illustrate my invention as applied to 45 a table for enameling cast-iron bath-tubs, Figure 1 is a plan view of the table with a bath-tub in position thereon. Fig. 2 is a side elevation. Fig. 3 is an end view of the same, and Fig. 4 a vertical transverse sectional view 50 on an enlarged scale.

A A designate the end framings upon which the table is supported and which may be either

bolted to the floor or upon a suitable movable carriage or truck.

Journal-bearings B B are formed on the 55 upper ends of the framings A A and receive journals C C, projecting from the ends of a heavy swinging beam D, the longitudinal axis of which is some distance below the longitudinal axis of the bearings C C. At the center 60 of the beam D a strong vertical shaft E is arranged in suitable bearings, and upon the lower end of said journal beneath the beam D a worm-gear F is fixed and meshes with a worm G, keyed upon a horizontal shaft H, 65 which has bearings on each side of the worm in hangers I I, that are bolted to the beam D, and has a third bearing in a box K, arranged on the side of a lever D', that extends laterally from the lever D. The shaft H extends 70 slightly beyond the lever D' and is provided with a handle H', by means of which it may be turned.

At a suitable point on the beam D a depending arm E' is fixed and an adjustable weight 75 E' is carried by said arm, being fixed in any position to which it may be adjusted by a setscrew E'. The purpose of the weight E' is to counterpoise the weight of the article being enameled, and while the adjustment of the 80 counterpoise-weight is not necessary when the articles being operated upon are of approximately the same weight such adjustment will be found necessary when it is desired to operate upon other articles varying considerably in weight from those previously operated upon.

The laterally-projecting lever D' is braced to the beam by a diagonal brace D², and provided with a handle D³. Upon the inner side 90 of the lever D' is arranged a latch comprising the pivoted handpiece d, the rod d', spring d², bell-crank lever d³, and sliding pin or catch d⁴, the handpiece d and bell-crank lever d² being pivoted to the lever d³ and to the rod 95 d', and the catch d⁴ being pivoted to the bell-crank lever d². Upon the inner side of the framing A an arc-shaped plate d⁵ is fixed, said plate being formed with notches d⁶ d⁷, into which the catch d⁴ is forced by the spring d² 100 when the handpiece d is released.

The vertical shaft E has attached to its upper end a cross-beam L, that supports a large metallic plate L', said plate being firmly at-

tached to the beam L by braces L² L². The beam L is formed with a longitudinal slot L³, in which are fitted slide-bars L⁴, formed with slots L⁵. Bolts L⁶ pass through the beam L and through the slots L⁵ in the slide-bars L⁴, and serve to guide the said slide-bars in their seats, while set-screws L⁷ serve to hold the slide-bars in any position to which they may be adjusted. The table M is provided with slots m m at each end, and through the said slots pass the shanks m' of clamps m², projecting upwardly from the slide-bars L⁴.

Near each end and on both sides of the beam L are arranged braces M² M², that extend laterally toward and near to the edge of the table M and are secured thereto by bolts M³ M³. Holes are bored at intervals through the table and through the lateral braces M² M², and through these holes are passed the downwardly-projecting ends n n of horizontal sides braces or clamps N N. Several such holes n² n² are provided, so that the side braces N may be adjusted to different positions to accommodate different sizes of articles. Curved arms O O project laterally from the ends n n of the side braces N, and from the ends of the said curved bars are hung swinging plates P P.

The apparatus constructed as described is operated in the following manner: Where it is desired to use the apparatus for handling articles to be enameled or otherwise treated, the structure is erected, or where it is mounted on a movable truck, the apparatus is moved to a suitable position at the furnace or place where treatment may be applied, the article to be operated upon is taken from the furnace or elsewhere, as the case may be, and is laid upon the table M, and if it is desired to change the position of the article for treatment in a furnace the handle H is turned until the table M has made sufficient revolution, when the article is lifted from the table and put back into the furnace. When the article is to be enameled, the side clamps or braces N N are fixed in position, their ends being inserted in such of the holes n² n² in the table as will allow of the article passing between the clamps, and the slide-bars L⁴ L⁴ so adjusted as to permit the article to be deposited between them. The article is then drawn from the furnace and lowered upon the table, so as to rest between the side clamps N N and the end clamps M' M'. The operator now grasps the handle D³ and releasing the catch d⁴, by means of the handpiece d, he raises the lever D', thus tilting the table L'. When the table has assumed the desired angle of inclination, the handpiece d is released and the catch d⁴ takes into one of the notches d⁵ in the arc-shaped plate D⁴, thus holding the table in the position to which it has been turned. The lower inside surface of the article as well as the upper outside surface of the article, when desired, is, by this movement of the table, brought to a horizontal or nearly

horizontal position, and the enamel can now be readily applied by operatives standing by the side of the table. The table is now caused to revolve on the shaft E by turning the handle H until the end of the bath-tub is in a horizontal or substantially horizontal position, whereupon the enamel is applied to the end either inside or outside, as desired. The revolution of the table is continued until the other side and the other end of the article have been successively brought into a horizontal position, when the operator, grasping the handle D³ and handpiece d, releases the catch d⁴ and draws the handle down until the table has assumed its normal or horizontal position, when the bottom of the article can be treated, and when completed the article may be lifted from the table and disposed of as desired.

Where tubs or other articles having rims are to be enameled, the enamel is usually applied to that part of the rim which is uppermost when the table is tilted; and in order to prevent the enamel from falling upon and adhering to the outside of the article I have provided the swinging plates P, one of which, when the table is tilted, will swing around, so that its inner edge comes under the inside of the rim of the article, so that any enameled material which may fall over the edge of the rim will be caught by the plate and prevented from falling upon the outside of the article.

Having described my invention, I claim—

1. In a revoluble and tilting table, the combination with supporting-framings, of a swinging beam having bearings in said framings, the axes of which are above the axis of the beam, and a revolving table supported on said beam and means for revolving the table and tilting the beam, substantially as described.

2. In a revolving and tilting table, the combination of a beam journaled in horizontal bearings, a lever connected to said beam, a vertical shaft journaled in the beam, a gear-wheel carried by said shaft, a worm meshing with said gear-wheel, a shaft to which said worm is secured, and a table mounted on said vertical shaft, substantially as described.

3. In a tilting table, the combination of a tilting beam having bearings above its longitudinal axis, and a revolving table mounted on said beam, with a lever connected to said beam, a notched plate arranged on the bearings of the beam, and a catch carried by said lever and adapted to engage said notched plate, substantially as described.

4. In a tilting table, the combination with a tilting beam mounted in suitable framings with the bearing parts of the beam above its central axis, of a table arranged on top of said beam, and a lever secured to the beam and adapted for tilting the same.

5. In an enameling-table, the combination of a tilting beam, a lever attached thereto, a

catch adapted to secure said beam in its adjusted positions, a revolving table mounted on said beam, mechanism carried by the beam and adapted to revolve said table and means 5 for holding the article on the table when the same is tilted.

6. In an enameling-table, the combination with the tilting table of swinging shields secured to the apparatus on said table and 10 adapted to protect the upper side of the articles on the table when the latter is tilted, substantially as described.

7. In an enameling-table, the combination with the table of clamps, slide-bars carrying 15 said clamps and means for securing said slide-bars when adjusted, substantially as described.

8. In an enameling-table, the combination with the end framings A, A, the beam D, 20 swinging on said framings by journals C, C, arranged above the central axis of said beam, the central shaft E, carrying worm-gear F, the shaft H, journaled on the beam and carrying worm G, meshing with said gear, the table M, mounted on said vertical shaft, the lever D', secured to the beam D, and means 25 substantially as described, for holding said

beam at different points of adjustment, substantially as described.

9. In an enameling-table, the combination 30 of a horizontally-arranged swinging beam, a vertical shaft carried by said beam, a table mounted on said vertical shaft, means for revolving said table carried by said beam, and means for tilting the beam also carried 35 by the beam, substantially as described.

10. In an enameling-table, the combination of a horizontally-arranged swinging beam, a table carried by said beam, means for tilting said beam with an adjustable counterbalance 40 attached to the beam, substantially as described.

11. In an apparatus for enameling, the combination with a rocking axle or beam, of a revoluble beam mounted on a vertical axis 45 on said rocking axle or beam and means for securing the article to be enameled to the revoluble beam, substantially as described.

In testimony whereof I affix my signature in presence of two witnesses.
